(57) **CLAIM**

The ornamental design for a bottle, as shown and described.

DESCRIPTION

FIG. 1 is a top-rear side perspective view showing a bottle;
FIG. 2 is a front side view of FIG. 1;
FIG. 3 is a rear side view of FIG. 1;
FIG. 4 is a right side view of FIG. 1;
FIG. 5 is a left side view of FIG. 1;
FIG. 6 is a top side view of FIG. 1;
FIG. 7 is a bottom side view of FIG. 1; and,
FIG. 8 is a bottom-front side perspective view of FIG. 1.
The broken lines show portions of the bottle that form no part of the claimed design.
